HARRY ALEXANDER, OF NEW YORK, N. Y., ASSIGNOR TO THE ALEXALITE COMPANY,
OF NEW YORK, N. Y., A CORPORATION OF NEW YORK.

ILLUMINATING DEVICE.

1,129,438.

Specification of Letters Patent. Patented Feb. 23, 1915.

Application filed January 2, 1913. Serial No. 739,705.

To all whom it may concern:

Be it known that I, HARRY ALEXANDER, a citizen of the United States, residing in the borough of Manhattan, city, county, and State of New York, have invented a certain new and useful Illuminating Device, of which the following is a specification.

This invention relates to devices for illuminating rooms, and other places, by indirect rays of light from incandescent electric lamps.

The objects of the invention are:—First: increased efficiency. Second: the avoidance of shadows and irregular illumination. Third: proper cooling of the fixture to prevent injury to the lamp. These and further objects will more fully appear in the following specification and accompanying drawings, considered together or separately.

In the drawings: Figure 1 is a sectional view of a device embodying my invention; and Fig. 2 is a plan view of the shield or diffuser.

In both of the views, like parts are designated by the same reference characters.

According to the preferred embodiment of my invention, I utilize a single, incandescent electric lamp of proper candle power, mounted in an inverted support and surrounded and shielded by an open, basin-like shield or diffuser, with a reflecting inside surface, which reflects the light upward against the ceiling, which, in turn, reflects and diffuses the light downward, without shadows or bright spots.

The lamp 1, may be of any shape, specifically as shown, or otherwise. It is carried in the socket 2, of any type, the latter being carried by the support 3. The support 40 is connected to the ceiling 4, which may be natural or artificial, as desired. A canopy 5 is shown at the upper end of the support 3, but this may be omitted, if desired.

The shield or diffuser 6, is supported in proper relation to the lamp. It is open at the top, as shown, without any inset bead or ornamentation at the edge; hence, no shadows can be cast by the edge of the shade. A bead 7, for strength and ornamentation, is shown on the outside of the edge, where it will cast no shadow.

The shield is conveniently supported from the support 3 by means of a bracket 8, and chains 9. I prefer to make the bracket 8 as shown in Fig. 1. This bracket has arms which extend outward and down-

ward on the sides of the socket 2. To the outer ends of the arms are attached the chains 9. These chains constitute a means for supporting the shield or diffuser. The 60 chains 9, as shown, are connected to the shield at a place removed from the inner edge of the shield. This arrangement of the chains brings them within the zone of the reflected light rays and any shadows, of the chains, cast 65 by the direct rays from the source of illumination will be intercepted by the rays reflected from the inner surface of the shield. This has the effect of preventing the chain from casting shadows. This is the preferred 70 embodiment, but the chains may be attached to any other part of the shield. Instead of a chain, any other suitable supporting means may be employed. The inner surface of the shield is preferably enameled, or 75 painted some light color. This I prefer to a highly polished surface, for the reason that bright spots are not cast by it, as is the case with a highly polished reflector. I prefer it to a glass reflector, for the further reason that dust will not appreciably 80 affect its efficiency to as great an extent.

I prefer to make the shield corrugated, as shown, the corrugations being in the form of concentric rings. This has the 85 effect of diffusing the light, as it will be reflected back and forth from side to side of the shield, due to the continually changing reflecting angle, finally issuing at an acute angle to the horizontal, and increasing the area of illumination of the 90 ceiling.

For the purpose of increasing the reflecting effect of the shield, I locate the lamp in such a position in relation to the shield that 95 its center of illumination is in, or approximately in, the focal point of the reflecting surface. To permit this to be done, it is necessary to distort the shape of the shield adjacent to the center, so that the bottom 100 of the lamp will not come in contact with the shield, while at the same time the filament of the lamp will be at the focal point of the reflecting surface. This is accomplished by dropping the center of the shield 105 to form a cup 10, of proper size so that the lamp may be lowered to such a point that the seat on the lower end will just avoid contact with the bottom of the cup.

I find that this lighting device is very 110 efficient, partly owing to the use of a single lamp, and also partly due to the corruga-

tions on the reflecting surface. The close proximity of the shield to the lamp, due to the necessity of placing the latter in the focal point, renders the lamp and shield very hot, which will reduce the life of the lamp, unless provision is made to ventilate it. For the purpose of ventilation, I provide a plurality of openings 11, in the bottom of the cup. I prefer to group these openings 10 around the center of the cup, as shown. I find that a single opening, in line with the center of the lamp, reduces the efficiency of the apparatus, while four openings grouped as shown, while having the same cross-sectional area of passage, will not affect the efficiency to so great an extent.

To prevent direct rays of light from passing downward, I attach a cap 12 to the bottom of the cup 10, at a sufficient distance to 20 permit the ready entrance of air to the passages 11. The inside of the cup may have the same finish as the inside of the shield, so that rays of light escaping through the passages 11 will be reflected back. The cap 25 12 is supported upon a stem 13, and secured in place by a nut 14, as shown, so that it may be removed for cleaning. A further advantage of the cup 10 is that it permits the lamp to be placed so low within the shield 30 that it will be shielded, and no rays will issue horizontally, and hence the lamp will not be directly visible. This is possible with a shield of comparatively small size, so proportioned as to secure the maximum diffusing and reflecting efficiency.

The attachment of the chains 9 to the shield, at some distance from the inner edge of the latter, allows the rays of light to strike the chains from all directions, and 40 shadows cast in one direction will be dissipated by light rays striking the chains from another direction; hence, no shadows will be cast by the chains, upon the ceiling.

The feature of supporting the lamp from 45 above, and independently of the shield, is very important, as I utilize all of the area of the inside of the shield as a reflecting surface, which would not be the case if the lamp were supported from below, and its 50 support passed through the shield.

In accordance with the provisions of the patent statutes, I have described the principle of my invention, together with the apparatus which I now consider to represent 55 the best embodiment thereof; but I desire to have it understood that the apparatus shown is merely illustrative, and that the invention may be carried out in other ways.

Having now described my invention, what 60 I claim as new and desire to secure by Letters Patent, is:—

1. An illuminating device which com-

prises, in combination, a reversed socket supporting an incandescent electric lamp, a support for the socket, an opaque diffusing 65 shield surrounding the lamp at the sides and below and having a reflecting inner surface, said shield being open at the top, and means connecting the support and shield, such means being connected to the shield within 70 the zone of the reflected light rays.

2. An illuminating device which comprises, in combination, a reversed socket supporting an incandescent electric lamp, a support for the socket, an opaque diffusing 75 shield surrounding the lamp at the sides and below and having a reflecting inner surface, said shield being open at the top, and means connecting the support and shield, such means being connected to the shield within 80 the zone of the reflected light rays and to the support above the socket.

3. An illuminating device which comprises, in combination, a reversed socket supporting an incandescent electric lamp, a support for the socket, an opaque diffusing 85 shield surrounding the lamp at the sides and below, and having a reflecting inner surface, said shield being open at the top, and means connecting the support and shield, such 90 means being connected to the shield inside the outer edge thereof and to the support above the socket.

4. An illuminating device, comprising, 95 in combination, a reversed incandescent electric lamp socket, a lamp, a support therefor, an opaque shield or diffuser surrounding the lamp at the sides and below and having a reflecting inner surface, said shield being open at the top, a bracket carried by the 100 support above the socket and having arms which extend out on each side of the socket, and means connecting the ends of the arms with the shield, such means being connected to the shield within the zone of the reflected 105 light rays.

5. An illuminating device which comprises, in combination, a reversed source of illumination and a support therefor, an opaque bowl having a reflecting inner surface supported in such a manner as to conceal the lamp from the sides and from below, concentric corrugations in the bowl to reflect and re-reflect the light rays, and supports for the bowl, said supports being 110 connected to the bowl within the zone of the reflected light rays.

This specification signed and witnessed this 31st day of Dec., 1912.

HARRY ALEXANDER.
